UNITED STATES PATENT OFFICE

EDWIN H. FOREMAN, OF NEW YORK, N. Y.

SWIM SUIT

Application filed December 23, 1931. Serial No. 582,727.

This invention relates to a swim suit.

An object of the invention resides in the provision of a swim suit, the upper portion of which is cut away to expose the back, under-arm portions, the shoulders and the neck of the wearer. In suits of this type, great difficulty has been encountered in causing the edges of the suit to lie snugly against the body of the wearer.

10 In United States Patent No. 1,813,043, dated July 7, 1931, the gapping of the edge of the garment adjacent the breasts of the wearer has been overcome in a manner described in that patent.

15 This invention causes the edge of the garment adjacent the back of the wearer to fit snugly, without necessitating the use of so much material as would interfere with the exposure of the back to the sun.

20 In the drawing, which illustrates one form of the invention,

Figure 1 is a view looking at one side and part of the front of the garment; and

25 Figure 2 is a view looking at the back of the garment.

30 In the form of garment illustrated in the drawing, the entire garment is formed preferably of knitted material and constitutes an upper body covering portion, a skirt, and trunks 2.

35 The front part of the body of the wearer is covered by a bib 3, which is cut away to expose the front portion of the neck at 4; the back opening 5 of the garment is defined by a curved edge 6, which merges at a point beneath the arms of the wearer with the edges 7, which extend to the rear of the breasts of the wearer.

40 Darts 8, such as described in the above-mentioned United States Letters Patent, are provided, with the result that the edges 7 snugly fit the body to the rear of the breasts. Because of the size of the back opening without

45 any support, the edge 7 would tend to gap away from the back of the wearer, and since a snug fit is desirable, I have provided means which will support the garment on the wearer and at the same time cause the edge 6 to fit the wearer snugly throughout the extent

of the edge, and yet which is of such construction that it does not seriously interfere with the exposure of the back of the wearer to the sun. This means comprises two relatively narrow straps 9, preferably of knitted material because of its elasticity, which are attached at 10 to the upper portion of the front bib 3 at points which lie in front of the shoulders of the wearer. Straps 9 extend to the edge 6 and are secured thereto at 10 on opposite sides of a vertical median line, which is shown in the drawing as a dot and dash line 11.

When the suit is on the wearer, the effect of these straps 9 is to hold the edge 6 from a point at the aforesaid medial line extending upwardly toward the edge 7 close to the body of the wearer, so that there will be a snug fit. However, the direction of force exerted by these straps 9 is such that they are not effective throughout the entire extent of the edge 6 to the points where it merges with edges 7; and, therefore, I have provided branch straps 12, which are secured at 13 to straps 9 and extend from the same in angular relationship, and are attached at 14 to the edge 6 on opposite sides of the medial line 11 and between the points of attachment 10 of the straps 9 to the edge 6 and points where this edge 6 merges with edge 7. The direction of pull of branch straps 12 extends at an angle to the direction of pull of the straps 9, and tends to draw the edge 6 toward the medial line and thus to cause the portions of the edge 6 not affected, or which are little affected, by straps 9, toward the body of the wearer, causing the garment to fit snugly.

The straps 9 and the branch straps 12, because of this triangular arrangement, may be made relatively narrow, so that they may easily be shifted to expose the covered portion of the back to the sun, and in any event so that they will cover relatively small areas.

When this invention is used in conjunction with the invention described in the aforementioned United States Letters Patent, a garment is produced which snugly fits the body of the wearer to the rear of the breasts, and snugly fits the back of the wearer, even

though the garment is cut low to such an extent that the back opening terminates at, or near, the waistline.

On the other hand, if this invention is used in conjunction with a garment in which other provision is made for fitting of the garment at the front of the body of the wearer, and in conjunction with a garment which has a low cut back, these straps will cause the back, nevertheless, to fit the wearer snugly.

10 What I claim is:

1. In a swim suit, a portion adapted to cover the lower part of the body of the wearer, a portion for covering the upper part of the body comprising a bib extending from the lower portion to points in front of each shoulder and bounded by a continuous arcuate edge from the shoulder points to the middle of the back at about the waistline whereby the shoulders, arms, under arms, neck and back are exposed, shoulder straps between the front shoulder points and the waistline edge at opposite sides of the median line of the back and an auxiliary strap from each shoulder strap to the continuous arcuate edge at a point more removed from the median line than the shoulder strap.

2. The swim suit of claim 1 wherein dart portions extend inwardly below the breast portion toward the center line of the garment thus shortening the normal length of the arcuate edge, which darts in cooperation with the auxiliary straps maintain a snug fit by keeping the arcuate edge close to the body.

In testimony whereof, I have signed my name to this specification this 19th day of December, 1931.

EDWIN H. FOREMAN.
